[57] CLAIM

The ornamental design for an illuminated floral sculpture, as shown and described.

DESCRIPTION

FIG. 1 is a front perspective view of an illuminated floral sculpture showing our new design, the conventional power cord being broken away for ease of illustration.

FIG. 2 is a rear perspective view of the illuminated floral sculpture.

FIG. 3 is a bottom plan view of the illuminated floral sculpture.

FIG. 4 is a top plan view of the illuminated floral sculpture.

FIG. 1

FIG. 2

FIG. 3
